(57) **CLAIM**

The ornamental design for a hand cover, as shown and described.

DESCRIPTION

FIG. 1 is an enlarged perspective view of the hand cover of the present invention;

FIG. 2 is a top plan view of the hand cover of FIG. 1, and showing the hand cover in an open configuration;

FIG. 3 is a bottom plan view of the hand cover of FIG. 1, and showing the hand cover in an open configuration;

FIG. 4 is a left side elevational view of the hand cover of FIG. 1, and showing the hand cover in an open configuration;

FIG. 5 is a right side elevational view of the hand cover of FIG. 1, and showing the hand cover in an open configuration;

FIG. 6 is a front elevational view of the hand cover of FIG. 1, and showing the hand cover in an open configuration; and,

FIG. 7 is a rear elevational view of the hand cover of FIG. 1, and showing the hand cover in an open configuration.
